UNITED STATES PATENT OFFICE

WAINO A. THOR, OF BERKELEY, CALIFORNIA

LOCK MECHANISM

Original application filed July 26, 1930, Serial No. 472,155. Divided and this application filed April 25, 1931. Serial No. 532,761.

My invention relates to improvements in lock mechanisms of the type disclosed in my copending application, Serial No. 472,155, filed July 26, 1930, and is a division of the 5 said application. The present invention consists in a lock mechanism wherein a push button of a door bell operates in conjunction with an adjustable combination mechanism to unlock a door when said push-button and 10 combination mechanism are placed in unlocking position by an operator.

The primary object of the present invention is to provide a new and improved door 15 unlocking mechanism.

Another object is to provide improved means for unlocking a door by pushing a 20 push-button.

A further object of the present invention is to provide an improved means for unlocking 25 a door which consists of a push-button and associated means set to unlocking position through said button.

A still further object is to provide improved combination means for unlocking a 30 door by means of a push-button, wherein said unlocking may be accomplished by means of a single or double combination.

I accomplish these and other objects by 35 means of the device disclosed in the drawings forming a part of the present application wherein like characters of reference are used to designate similar parts throughout the specification and drawings, and in which—

Fig. 1 is a broken transverse section of a 40 casement and door with my improved fitting mounted thereon;

Fig. 2 is a similar view showing the device in bell ringing position, and including 45 a conventional wiring diagram of the electrical connections;

Fig. 3 is a front view of the fitting;

Fig. 4 is a front view of the locking members in locking position;

Fig. 5 is a view similar to Fig. 4 with the 50 locking members in unlocking relation; and

Fig. 6 is a back view of the locking members.

Referring to the drawings, the numeral 1 55 is used to designate in general a door mounted within a casement 2 and provided with the

usual latch bolt 3 entering an opening 4 in the adjacent face of the casement to secure the door in closed position.

My invention comprises a plunger shaft 6 55 slidably and rotatably mounted within a housing member designated in general by the numeral 7 and mounted within a recess 8 formed in the casement. The shaft is supported at its inner end by a bearing portion 9 formed upon the inner end of the housing 60 7, and the outer end of the shaft is provided with a knob 11 slidably feathered to the shaft 6 and rotatably supported by a face plate 12 threaded or otherwise secured to the outer end of the housing 7 and seated within a recess 65 13 formed in the outer face of the casement.

The inner end of the plunger shaft 6 is provided with a latch actuating member 14 rotatably engaging a reduced portion 16 70 formed upon said inner end of the shaft, and held thereon by a suitable retaining nut 17. The member 14 extends laterally into a slot 18 formed in the casement opposite the latch 3 and is provided with a beveled face 19 engaging the beveled end of the latch bolt 75 15 whereby an axial inward movement of the shaft 6 causes the face 19 to press the latch 3 inwardly to door releasing position, as indicated in dotted lines in Figs. 1 of the drawings. The member 14 is guided and held 80 against rotation by the slot 18.

A locking member 21 is slidably keyed to the shaft 6 within the housing 7, said member being provided with an annular flange portion 22 seating within a recess 23 formed in an annular locking member 24 slidably and rotatably mounted within the housing. The member 24 is provided with a pair of apertures 26 preferably arranged upon opposite sides thereof and slightly offset with respect to a diameter passing thru the axis of the member 24 and one of said apertures for a reason hereinafter more fully explained. The member 21 is provided with a pair of notches 27 formed in the periphery of the flange portion 22 in the same relative relation as the apertures 26 and movable to register with said apertures as hereinafter more fully described.

A plate 28 is slidably keyed within the 100

outer end of the housing 7, said plate 28 having a central aperture permitting sliding movement of the shaft 6 therethru. A pair of pins 29 are secured upon the plate 28 to extend inwardly in parallel relation to the shaft 6, said pins being arranged in the same relative relation as the apertures 26 and notches 27 whereby said pins may pass thru said apertures 26 and notches 27 when in registering relation. The inner ends of the pins 29 extend thru apertures 31 formed in a partition 32 mounted within the housing 7 to support and guide the pins in accurately alined positions. Springs 33 are mounted around the pins 29 between the partition 32 and the plate 28 to normally move the plate outwardly against a collar 34 secured upon the shaft 6. The collar 34 abuts against the inner end of a bearing portion 11', formed upon the knob 11, and a nut 36 is threaded onto said portion 11' to retain the knob in operative assembled relation to the face plate 12, thereby limiting the outward movement of the shaft 6 and plate 28 as actuated by the springs 33.

A collar 37 is mounted upon the locking member 21. The collar 37 is provided with a radially disposed arm 38 arranged to engage a pin 39 extending rearwardly from the inner face of the locking member 24 whereby rotation may be imparted from the collar 37 to the locking member 24. The collar 37 is arranged to be adjustably secured to the locking member 21 for rotation therewith, preferably by means of a serrated face 41 engaging a correspondingly serrated face of a shoulder 42 carried by the member 21. The collar 37 is normally held in proximate relation to the shoulder 42 with the serrations thereof in inter-engaging relation by any suitable means, such as a spring 43 whereby the collar 37 may be moved to disengage the shoulder to permit the collar and arm 38 to be adjusted angularly to desired positions, and to change the combination or unlocking position as indicated by the knob 11.

The locking member 21 is provided with an annular flange 44 upon its inner end and contacts, under certain conditions, with electrical terminals 46 mounted in insulating bushings 47 in turn mounted in the inner end of the housing 7. A conductor 48 leads from one terminal to the usual door bell indicated at 51 while a second conductor 53 returns from said bell to a source of electrical energy 52 and from thence by a third conductor 49 to the opposite terminal 46. Therefore, when in ordinary use as a door bell the push-button or plunger shaft 6, when pressed inwardly, moves the member 44 to close the gap across the terminals, and against the tension of a spring 50 which tension operates to break contact of the plate 44 with the terminals 46 when pressure on the plunger 6 is released.

The knob 11 is feathered to the outer end of the shaft 6 in any of a plurality of keyways 54 whereby said knob may be set in any desired angularly adjusted position relative to the shaft. The knob 11 is provided with a dial portion having calibrations 56 marked thereon and readable with respect to a fixed index 57 marked upon the face plate 12 whereby the knob 11 and shaft 6 may be rotated through desired angles of movement in either direction, the degree of such movement being indicated by the calibrations.

The operating mechanism constructed substantially as illustrated and as above described is assembled into the housing 7, and the face plate 12 secured thereon. The housing is then inserted into the recess 8 from the front of the casement and secured therein by a plate 58 and securing bolts 59 extending into engagement with the inner end of the housing 7 thru the inner face of the casement 2 and on opposite sides of the bearing 9 of the housing 7, whereby access may be had to the mechanism from inside the door when necessary, but preventing tampering by unauthorized persons from without.

In operation, the locking members are normally turned with the notches 27 out of registration with the apertures 26, as disclosed in Fig. 4 of the drawings. In this relation, when pressure is applied upon the outwardly extending end of the shaft 6, the shaft is moved inwardly and the inner ends of the pins 29 are moved against the locking members 24 and 22, thereby causing the said locking members to be moved inwardly until the flange 44 is moved into contact with the ends of the contacts 46, thereby preventing the full movement of the plunger 6 and its member 14 necessary to unlock the latch 3.

The mechanism may be set either for a single or double combination for unlocking, in the following manner:

By changing the relative position of the serrated collar 37 to the shoulder 42 of the member 21 so that when the pin 38 engages one side or the other of the pin 39 when the notches 27 register with the apertures 26, it is then only necessary to rotate the knob 11 thru at least one complete revolution and then turn the proper graduation 56 on the knob or combination dial 11 to register with the index 57, which setting is, of course, known to an authorized operator, which will register the aligned notches 27 and apertures 26 with the pins 29 on the plate 28. Pressure on the button or plunger 6 will then move said pins 29 thru the registered or aligned notches and apertures and permit sufficient movement of said plunger 6 to unlock the latch 3.

Or, the serrated collar 37 may be set relatively to the shoulder 42 so that when the pins 38 and 39 contact the notches 27 and apertures 26 will be non-registering, in which case the

knob 11 is turned to set the plate 24 with its apertures 26 opposite or in registration with the pins 29 and then by reversing the movement of the knob 11 the member 21 and its flange 22 may be rotated to set or register the notches 27 in register with the already registered apertures 26 and pins 29. The proper registering positions, as indicated by the knob 11, being known to the operator.

10 When the apertures 26, notches 27 and pins 29 are aligned or registered the plunger 6 is moved inwardly and as the pins 29 move thru the registered notches and apertures the member 14 by means of its beveled surface 15 19 engages and retracts the latch 3 of the door 1 so that the door may be readily opened.

After the door is opened and pressure on the plunger 6 released the springs 33 on the pins 29 will move the plate 28, collar 34 and 20 hence the plunger 6 to normal position. A slight rotation of the knob 11 will unregister the notches and apertures from the pins 29 and if the plunger 6 be now pressed inwardly said pins 29 will move the member 21 and its 25 associated parts against the terminals 46 which serve as a stop to prevent further movement of said plunger.

It is to be understood that the member 24 is rotatably mounted within the housing 7 30 with sufficient friction to permit rotation thereof only when moved by the pin 38. As the spring 50 is constantly pressing upon the said member 21 and associated parts, the plate or member 24 is normally moved against 35 stops 55 which hold said member 24 in spaced relation to the ends of the pins 29.

While I have illustrated and described my invention in only one specific embodiment, the specific details of construction and arrangement are subject to modification in a great variety of ways without departing from the spirit of my invention. I therefore do not wish to be restricted to the specific structure as illustrated and described, but 45 desire to avail myself of all modifications which may fall within the scope of the appended claims.

Having thus described my invention, what I claim as new and desire to secure to Letters 50 Patent is:

1. A door fitting comprising a member mounted within a door casement, said member being rotatably and axially slidably within the casement; means mounted upon the inner end of the member for displacing the latch of a door mounted within the casement to a door releasing position; means normally preventing axial movement of the shaft to latch displacing position, said means being 55 adapted to be manually manipulated from outside the door to a releasing position whereby said member may be moved axially to a door releasing position.

2. A door fitting comprising a shaft slidably rotatably mounted within a door case-

ment; latch actuating means mounted upon the inner end of the shaft and movable by an axial movement of the shaft to displace a door latch to a door releasing position; a pair of relatively rotatable locking members 70 mounted upon the shaft and having apertures movable to registering relation when the locking members are in unlocking relation; means operable from outside the casement to move the locking members to unlocking relation; means mounted in connection with the shaft and movable axially therewith to engage the locking members when in locking position and to enter the registering apertures when in unlocking position, the 80 locking members being movable axially with the shaft when in locking relation; and means limiting the axial movement of the shaft and locking members when said locking members are in locking position to prevent 85 displacing the latch.

3. A door fitting comprising a shaft slidably and rotatably mounted within a door casement; latch actuating means mounted upon the inner end of the shaft and movable by an axial movement of the shaft to displace a door latch to door releasing position; a pair of relatively rotatable locking members mounted upon the shaft and having apertures movable to registering relation 90 when the locking members are in unlocking relation, one of said members being feathered to the shaft and the other being rotatable relative thereto and frictionally engaged within the casement; means for imparting 95 rotation from the keyed member to the rotatable member; a combination dial feathered upon the outer end of the shaft for turning the shaft and locking members to unlocking position; pins carried by the shaft and movable axially therewith to engage and move the locking members when in locking relation and to pass through the registering apertures without moving the members when in unlocking relation; and means limiting 100 the axial movement of the shaft and locking members when said locking members are in locking relation to prevent displacing the latch.

In witness whereof, I hereunto set my sig- 115 nature.

WAINO A. THOR.
